Inventor.

Edward J. Birkett.
E. J. Burgess

UNITED STATES PATENT OFFICE.

EDWARD J. BIRKETT, OF MILWAUKEE, WISCONSIN, ASSIGNOR TO THE
MILWAUKEE HARVESTER COMPANY, OF SAME PLACE.

PITMAN-HOLDER.

SPECIFICATION forming part of Letters Patent No. 666,794, dated January 29, 1901.

Application filed June 7, 1900. Serial No. 19,421. (No model.)

To all whom it may concern:

Be it known that I, EDWARD J. BIRKETT, a citizen of the United States, residing at Milwaukee, in the county of Milwaukee and State of Wisconsin, have invented new and useful Improvements in Pitman-Holders, of which the following is a specification.

My invention relates to improvements in pitman connections for harvesters and mowers; and the object of my improvement is to provide a pitman connection that may be readily disconnected without the use of tools and one that will securely retain the parts in connection when so adjusted. I attain this object by the mechanism illustrated in the accompanying drawings, in which—

Figure 1 is a plan view, partly in section, of my invention. Figs. 2, 3, 4, and 5 are representations in detail of the different operative parts.

Like numerals refer to like parts throughout the several figures.

1 is the crank. It may be a crank-wheel. 2 is the wrist-pin. It is formed with a tubular bore 3, which may extend entirely through the crank. The bore at its outer end is partly closed by means of the bridge 4. 5 is a retaining-key having the stem portion 6 adapted to enter the bore 3 and the collar portion 7 of greater diameter than the wrist-pin 1. An opening 8 is made through the larger end of the key, and upon each side of the opening are small ears 9, projecting outward from its face, and a plate-spring 10 is secured to the key, leaving its free end projecting through the opening 8. The plate-spring 10 has an offset 11, adapted to engage with the bridge 4 of the wrist-pin, and the ribbed sides 12 of the key rest against the bridge and prevent the key from revolving within the wrist-pin. The ears 9 are designed to shield the projecting end of the spring. The same mode of construction is employed in connecting the opposite end of the pitman to the sickle-head. 45 The sickle-head is provided with a pin corresponding with the wrist-pin, and the retaining-key is a duplicate of key 5.

The operation of my invention is as follows: The pitman is placed in position on the wrist-

pin. The retaining-key is pushed into the bore 50 of the wrist-pin. The plate-spring yields under the pressure until the offset portion has reached a position inside of the bridge 4, when it reacts and causes the offset to engage with the bridge, and the collar being of greater 55 diameter than the wrist-pin holds the pitman securely against lateral displacement.

My invention is applicable to all mechanisms employing pitmen with wrist-pin connections and is especially designed to facilitate the removal of the pitman of a harvester or mower cutting apparatus, which is frequently necessary in order that the sickle may be withdrawn.

What I claim as my invention, and desire 65 to secure by Letters Patent, is—

1. In a pitman connection, the combination of a pitman, a wrist-pin and a retaining-key, said wrist-pin having a central longitudinal bore adapted to receive the retaining-key, a 70 plate-spring having an offset, and said wrist-pin provided with a bridge portion extending across one end of the longitudinal bore, and adapted to engage with the offset portion of the spring. 75

2. A pitman-retaining key adapted to enter an axial bore of a wrist-pin, and provided with a head having a greater diameter than the wrist-pin, and an opening through the head, and a plate-spring having one end secured to the key, and its free end projecting through the opening, said spring having an offset adapted to engage with the wrist-pin. 80

3. In a pitman connection, a wrist-pin and a pitman in combination therewith, said wrist-pin having an axial bore adapted to receive a pitman-retaining key, and having a bridge 85 across one end of the bore.

4. In a pitman and sickle-head connection, the combination of a sickle-head having a 90 stem adapted to receive a pitman, said stem having an axial bore adapted to receive a retaining-key, and means within said stem for holding the key against lateral displacement.

EDWARD J. BIRKETT.
